FRONT TIGHTENER FOR SAFETY SKI BINDINGS
Hannes Marker, Alspitzstrasse 37, Garmisch-
Partenkirchen, Germany
Filed May 8, 1964, Ser. No. 365,983
Claims priority, application Germany, May 18, 1963,
M 56,886
8 Claims. (Cl. 280—11.35)

This invention relates to a front tightener for ski bindings, in which tightener the tightener lever is pivoted to a bracket, which is adjustable in the longitudinal direction of the ski and from which an adjusting element extends forwardly and is supported by a retaining bracket secured to the ski. In known front tighteners of this type, the adjusting element consists of a slide member, a screw, a rod or the like of metal. The co-acting adjusting and locking parts may become iced so that the tightener can no longer be adjusted under certain weather conditions.

In a front tightener of the type described first hereinbefore, this disadvantage is avoided according to the invention in that the adjusting element is flexible and provided with means for securing the adjusting element to the retaining bracket by interlocking with this bracket. Owing to its flexibility, the adjusting element is not susceptible to icing because any adhering ice can easily be broken off by a movement of the adjusting element so that the tightener can be adjusted even when touring under very cold winter condition.

In a development of the invention, the adjusting element consists of a flat, bandlike strip, particularly a flat, elastic band of plastics material, and this strip extends on or is closely spaced from the surface of the ski. This design results in a tightener having a lower overall height than has been achieved so far. It must be borne in mind that a guiding device for the bracket which carries the tightener lever is not required because it is not necessary to protect the adjusting element from being deflected, whereas such protection of the metallic adjusting elements had previously to be afforded by a sliding guide or the like for the bracket.

The manufacture will be particularly simplified if the band of plastics material forms a unit of construction with the bracket which carries the tightener lever so that this bracket is also made from the plastics material. The band of plastics material may suitably be provided with a reinforcement of metal wire. Alternatively, the adjusting element may consist of a band of braided metal wire.

For interlocking the adjusting element with the retaining bracket, a rocker lever is suitably pivoted to this bracket and arranged in such a manner that locking elements of the rocker lever and of the adjusting element interlock in the closed position of the rocker lever. The locking elements co-acting with the adjusting element may alternatively be provided on a separate pressure plate, which is guided by the retaining bracket and is movable to the locking position preferably by a rocker lever.

A preferred embodiment of the invention will be explained more fully hereinafter with reference to the drawing, in which

FIG. 1 is a side elevation showing the front tightener according to the invention with the tightener lever in closed position.

FIG. 2 is a top plan view showing the tightener, with the parts which are covered by the tightener lever and the yokelike tension member being shown in broken lines, and

FIG. 3 is a side elevation, partly in section, showing the open front tightener;

2

FIG. 4 is a side elevation, partly in section, of an alternative form showing the rocker lever, acting on a separate pressure plate.

The retaining bracket 3 is secured with screws 2 to the ski 1. A rocker lever 4 which is forwardly movable to its closed position is pivoted at 5 to the retaining bracket 3 and in the embodiment shown by way of example is formed on its underside with two riblike elevations 6, which extend transversely to the longitudinal direction of the ski. A yokelike pulling element 9 for the cable 10 of the binding is pivoted at 8 to the tightener lever 7, which is pivoted at 11 to a bracket 12, which is freely slideable on the surface of the ski and, as is apparent particularly from FIG. 2, has a supporting surface which is rearwardly enlarged in triangular configuration. In the embodiment shown by way of example, a band 13 of plastic material is secured to this bracket 12. To this end, one flange of the T-shaped rear end of this band engages a bolt 14 from behind, which bolt is riveted to the side plates of the bracket 12, and the other flange of said T-shaped end engages a slot formed in the base plate of the bracket 12. As has already been mentioned, the bracket 12 could form a unit of construction with the band 13 of plastics material so that the manufacture can be considerably simplified and reduced in cost.

The band 13 of plastics material may consist, e.g. of Nylon (registered trademark) or another plastics material which resists tensile stress but has flexural elasticity. The band 13 is provided in its front portion with transversely extending grooves 15, with which the transverse ribs 6 of the rocker lever 4 can be engaged. This results in a simple manner in a locking engagement between the retaining bracket 3 and the tape 13. When the rocker lever 4 has been pivotally moved upwardly, the tape 13 and with it the tightener lever 7 and the cable 10 of the binding can be adjusted in the longitudinal direction of the ski 1. The rocker lever 4 is then lowered until the locking engagement has been effected.

It will be readily apparent that an icing of the tightener which has been described hereinbefore cannot have detrimental results because any ice covering can be broken off simply by bending the elastic band 13 of plastics material, whereafter the adjustment may be effected.

The embodiment shown by way of example may be modified in various respects. The surface irregularities of the tape 13 co-acting with corresponding locking parts of the rocker lever need not consist of transverse grooves but may consist of very small teeth, recesses of any desired shape, or the like, which face corresponding locking means on the rocker lever. It would also be possible to provide the locking elements on a pressure plate, which is guided in the retaining bracket and may be subjected, i.e., to the action of a rocker lever, which forces the plate against the corresponding locking elements of the band. The band might be made, e.g., from braided metal wire, or a Nylon rope or a wire cable might be used, which extends through the retaining bracket. In this case it would be necessary to provide the retaining bracket with a semi-circular shell, which contains locking elements, and a second half-shell having the same surface structure must be adapted to be lowered by means of the rocker lever or the like in such a manner that the rope or cable is locked in the retaining bracket.

One example of the use of a pressure plate is depicted in FIG. 4, like reference numerals being used to denote structure similar to that in the previous figures. In the arrangement of FIG. 4, the retaining bracket 23 is provided with a slot 27 in which is disposed pressure plate 25. Two riblike elevations 26 are formed on the underside of plate 25, extend transversely to the longitudinal direction of the ski, and engage with grooves 15

of band 13. Rocker lever 24 is pivotally mounted on retaining bracket 23 and is provided with a cam surface which, upon pivotal movement of the lever, acts to force the elevations 26 of plate 25 against the corresponding grooves 15 of band 13 to effect the locking arrangement.

The embodiments of the invention in which an exclusive property or privilege is claimed are defined as follows:

1. A front tightener for ski bindings comprising a first bracket which is adjustable in the longitudinal direction of the ski, a tightener lever pivotally mounted on said first bracket, heel engaging means pivotally connected to said lever for adjustment thereby in the longitudinal direction of the ski, a retaining bracket secured to said ski at a point spaced forwardly of said first bracket, an adjusting element attached to and extending forwardly of said first bracket and being supported at its forward end by said retaining bracket, said adjusting element being flexible, and means for securing the adjusting element in interlocking engagement with said retaining bracket.

2. A front tightener for ski bindings according to claim 1 wherein the adjusting element consists of a band-like strip of flexible material which lies closely adjacent the upper surface of said ski.

3. A front tightener for ski bindings according to claim 2 wherein the adjusting element consists of a flat elastic band of plastic material.

4. A front tightener for ski bindings according to claim 3 wherein the band of plastic material is rigidly attached to said first bracket.

5. A front tightener for ski bindings according to claim

3 wherein metal wire reinforcement means are made integral with said band of plastic material.

6. A front tightener for ski bindings according to claim 2 wherein the adjusting element consists of a strip of braided metal wire.

5 7. A front tightener for ski bindings according to claim 1 wherein said securing means includes a rocker lever pivotally mounted to said retaining bracket, and locking elements on the rocking lever and on the adjusting element, said locking elements engaging in the closed position of said rocking lever.

10 8. A front tightener for ski bindings according to claim 1 wherein said securing means includes a pressure plate having locking elements coacting with the adjusting element, said pressure plate being guided by the retaining bracket and being movable to the locking position, preferably by a rocking lever.
